UNITED STATES PATENT OFFICE.

EMIL KRESSE, OF PHILADELPHIA, PENNSYLVANIA.

MUTE HOLDER.

Application filed December 18, 1922. Serial No. 607,474.

To all whom it may concern:

Be it known that I, EMIL KRESSE, a citizen of the United States, residing at Philadelphia, in the county of Philadelphia and 5 State of Pennsylvania, have invented certain new and useful Improvements in Mute Holders, of which the following is a specification.

My invention relates to mute holders adapted for use on string musical instruments such as a violin, viola, cello, etc., and 10 has for its object to provide a holder which will hold a mute in a convenient position on the instrument and to construct it so that, when holding the mute, it will cause no vibration or chattering tones.

This object, and other advantageous ends which will be described hereinafter, I attain in the following manner, reference being had to the accompanying drawings in which—

20 Figure 1 is a plan view of a violin having my invention applied thereto,

Figure 2 an enlarged side elevation of a mute holder constructed in accordance with my invention,

25 Figure 3 a view similar to Figure 2 partly in section, and

Figure 4 a perspective view of a spring clip which forms a part of my invention.

Referring to the drawings, 1 is a violin, 30 2 a bridge, 3 the strings passing over the bridge and connected to one end of a tail-piece 4, the other end of which is held by the violin in the usual manner. A U-shaped spring clip 5, made from a strip of metal is secured to the tail-piece by screws 6, and includes supporting legs 7 having an integral bent spring body 8 between the legs of the

35 U. The spring body is preferably bent at its center inwardly toward the tail-piece so that the bent part will engage the center prong of a mute 9, and the part of the spring body near the supporting legs will engage the side prongs of the mute and thereby hold it in position.

When playing the violin and it is desired 45 to play intervening parts with a mute, the mute may be very easily slipped from the spring clip and placed on the bridge. Likewise when it is desired to play without the mute, the mute can be slipped on the spring 50 clip without changing the holding position of the violin.

While I have described my invention as taking a particular form, it will be understood that the various parts of my invention 55 may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. The combination with the tail piece of 65 a stringed instrument, of a U-shaped spring strip, having its legs secured to the tail piece, bent centrally between the legs for holding a mute between its prongs.

2. The combination with the tail piece of 70 a stringed instrument, of a U-shaped spring strip, having its legs secured to the tail piece, bent between the legs inwardly toward the tail piece for holding a mute between its prongs.

3. A mute holder bent from a strip of 75 metal into U-shape and having the ends of the legs of the U bent outwardly to form attaching parts and the center part of the U bent between the legs for holding a mute between its prongs.

In testimony whereof I have signed my name to this specification in the presence of two subscribing witnesses.

EMIL KRESSE.
